ATTORNEY,

UNITED STATES PATENT OFFICE.

JOSEPH W. WOOD, OF BARABOO, WISCONSIN, AND ALVINUS B. WOOD, OF TACOMA, WASHINGTON TERRITORY.

ROPE-CLAMP.

SPECIFICATION forming part of Letters Patent No. 393,952, dated December 4, 1888.

Application filed May 16, 1888. Serial No. 274,047. (No model.)

To all whom it may concern:

Be it known that we, JOSEPH W. WOOD, of Baraboo, in the county of Sauk and State of Wisconsin, and ALVINUS B. WOOD, of Tacoma, in the county of Pierce and Territory of Washington, have invented a new and Improved Rope-Clamp, of which the following is a full, clear, and exact description.

Our invention relates to an improved rope-10 clamp, and has for its object to provide a tripping device adapted more particularly for attachment to the several binding-strands of a rope or chain utilized for hoisting or elevating hay or equivalent material, whereby the several strands are united beneath the load in the device, and wherein the said device is used to release the ropes by which the load is held expeditiously and conveniently and the load is deposited in the desired place.

20 The invention consists in the construction and combination of the several parts, as will be hereinafter fully set forth, and pointed out in the claims.

Reference is to be had to the accompanying 25 drawings, forming a part of this specification, in which similar figures of reference indicate corresponding parts in both the views.

Figure 1 is a side elevation of the device, partially in section, illustrating the carrier attached thereto; and Fig. 2 illustrates a modification of that portion of the carrier adapted for attachment to the clamp.

The body 10 of the device is preferably made of metal cast in one piece, the said body being 35 provided with a recess in its upper end, whereby ears 11 are formed, and also with a transverse recess, 12, at or near the center. Below the recess 12 an opening, 13, is provided, which opening is located near the base of the device 40 intersecting the under portion of the aforesaid recess 12, as clearly illustrated in Fig. 1. Upon one side of the device adjacent to the opening 13 a tubular projection, 14, is formed, which projection constitutes an integral portion of 45 the body.

Between the ears 11 the upper end of the hook 15 is pivoted, the lower extremity of which hook is provided with an outwardly-extending lip, 16, the upper wall of the recess 50 12 being inclined or curved outward in the di-

rection of the said hook for the better reception of the same.

In the recess 12, immediately above the opening 13, a lever, 17, is pivoted, which lever projects outward at each side of the body, extending farther upon that side to which the tubular projection 14 is attached. In the end of the lever 17, over the tubular projection 14, is an aperture, 18, and adjacent to said aperture, in the upper end of the lever, an angular recess, 19, is formed, which recess is adapted for the reception of the lip 16 of the hook.

Near the opposite end of the lever 17, also upon the upper side, a lug, 20, is cast, upon which lug one end of a spring, 21, is secured, the said spring being adapted at its other end for reception in a diagonal bore, 22, formed in the body of the device.

A trip-rope, 23, is projected upward through the tubular projection 14 and secured to the lever 17 at the apertured end 18, and a rope, 24, is secured in the body-opening 13.

In operation we utilize four binding-ropes—the rope 24 and three others, respectively numbered 25, 26, and 27—each of which ropes 75 at one end is provided with an eye, as shown in Fig. 1, or an attached link, as illustrated in Fig. 2. The other ends of the said ropes are to be united by tying, or in any approved manner, above the bundle of hay or other material to be elevated, as hereinafter set forth. To unite the strands, the hook 15 is released from the lever 17, and the eye of the central strand, 27, is passed through the eyes of the several side strands, 25 and 26, the eye of the 85 aforesaid central strand, 27, being also passed over the hook 15, which hook is thereupon carried inward to an engagement with the lever 17, which is its normal position. The side strands, 25 and 26, are prevented from working sidewise by means of a large knot, 28, formed upon the central strand, 27, above the eye thereof, or by other approved means.

In the further operation of the device it is laid in position to receive the hay or other material to be built upon it. The four ropes or chains 24, 25, 26, and 27 are connected in the center by the device and cross each other at right angles as nearly as may be convenient. When the load is received, the said ropes are 90 95 100

brought together and united on top of the load, 24 to 27 and 25 to 26, in any approved manner.

The hoisting-tackle is secured to the united strands and the load carried to the desired place, whereupon the trip-rope 23 is given a quick jerk, carrying the lever 17 downward, whereby the hook 15 is released from the recess 19, permitting the ready detachment from the hook of the eye of the strand 27 of the carrier. The weight of the hay will now force the eyes of the side strands out of engagement with the eye of the strand 27, permitting the ready escape of the hay or material carried.

Having thus described our invention, what we claim as new, and desire to secure by Letters Patent, is—

1. In a rope-clamp, the combination, with a body provided with an attached tubular projection at one side, and a horizontal opening approximating the base, and an essentially central recess, of a spring-actuated lever pivoted in the recess, a hook pivoted in the upper end of the body engaging said lever, and a trip-rope secured to the outer end of the lever and extending downward through said tubular projection, as and for the purpose specified.

2. The combination, with a body provided with a horizontal opening near the base, a tubular projection upon one side, and an essentially central transverse recess above and intersecting the said opening, of a spring-actuated lever pivoted in said recess, provided with

an angular notch in its upper surface, a hook pivoted in the upper extremity of the body engaging the angular notch in said lever, and a trip-rope secured to one end of the lever, as and for the purpose specified.

3. The combination, with a body provided with a lower transverse opening, a tubular projection at one side, and an essentially central recess intersecting the said opening, a spring-actuated lever pivoted in the recess, provided with a notch in its upper surface, and a hook pivoted in the upper end of the body having an outwardly-flaring lip engaging the notch of the lever, of a trip-rope attached to one extremity of the lever, passing downward through the tubular projection, and a carrier consisting of four strands adapted to be united at their upper ends and provided with eyes at their lower ends, the eyes of the side strands slipping over the eye of a cross-strand, and the eye of the said cross-strand being adapted for engagement with the pivoted hook, the other strand being attached to the lower portion of the device, substantially as and for the purpose specified.
